(57) **CLAIM**

The ornamental design for a letter tray, as shown and described.

DESCRIPTION

FIG. 1 is a top, front, right side perspective view of a first embodiment of a letter tray showing my new design;

FIG. 2 is a bottom, rear, right side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;
FIG. 9 is a top, rear, right side perspective view of a second embodiment of a letter tray showing my new design, the right-side-elevational, and left-side-elevational views being the same as shown in FIGS. 7 and 8 respectively;

FIG. 10 is a top, front, right side perspective view thereof;

FIG. 11 is a top plan view thereof;

FIG. 12 is a bottom plan view thereof;

FIG. 13 is a top, front, right side perspective view of a third embodiment of a letter tray showing my new design, the rear-elevational, right-side-elevational, and left-side-elevational views being the same as shown in FIGS. 6, 7, and 8 respectively;

FIG. 14 is a bottom, rear, right side perspective view thereof; and,

FIG. 15 is a top plan view thereof.
